UNITED STATES PATENT OFFICE.

FRED MOORE, OF AURORA, ILLINOIS.

TRUNK BED.

Application filed August 30, 1921. Serial No. 496,879.

To all whom it may concern:

Be it known that I, FRED MOORE, a citizen of the United States, residing at Aurora, in the county of Kane and State of Illinois, 5 have invented certain new and useful Improvements in Trunk Beds, of which the following is a specification, reference being had therein to the accompanying drawings.

This invention relates to a trunk bed, and 10 the object of the invention is to provide an apparatus that is suitable for the use of campers and army officers, and, at the same time, providing a bed.

With this and other objects in view, my 15 invention comprises certain novel combinations, constructions and arrangements of parts as will be hereinafter described, illustrated in the accompanying drawings, and more particularly pointed out in the ap- 20 pended claims.

In the drawings:

Figure 1 is a perspective view of the apparatus used as a bed.

Figure 2 is a perspective view of the 25 trunk bed in a closed condition.

Figure 3 is a transverse, vertical, sectional view of the trunk bed, as shown in its closed position, Fig. 2.

Referring to the drawings by numerals, 1 30 designates the casing of my apparatus, which is made of comparatively thin, yet strong and durable material, and the bed is reinforced by metal pieces 2, at its corners, for increasing the life and strength 35 of the entire apparatus. The door 3 is hinged, at 4, along the upper edge of the front, and the door is adapted to close down flat upon the top 5, of the casing 1, for the purpose hereinafter specified. A plu- 40 rality of drawers 6 are placed in the casing 1, with a compartment 7 formed in the casing in front of the front ends of the drawers 6.

A spring mattress 8 comprises the central 45 section 9 and end sections 10. When the apparatus is in its closed or compacted condition, the mattress 8 is in compartment 7, thereby being placed out of the way, when not in use, and at the same time holding the 50 drawers 6 closed, so that they will not spill

their contents; the mattress 8 in compartment 7, Fig. 3, acts as a locking means for preventing the drawers 6 from sliding out of position.

When the mattress is in position for a 55 person to lie down on the same, it rests upon the door 3, and door 3 rests flat upon top 5; the door increases the strength of the top to about double, as the door when closed upon the top, as shown in Fig. 1, 60 constitutes a part of the top for supporting the weight of the mattress and the object reposing thereon, whereas if the door 3 was not used, the top of my trunk bed would be marred, as well as being strained; by the 65 mattress engaging the inner face of the door, as the door rests flat upon the top, Fig. 1, the marring will not take place on an outer surface of the trunk bed, and further, the portion of the trunk bed supporting the mattress will be greatly strength- 70 ened and doubly reinforced by reason of the top 5 and the door 3 being the parts of the casing that supports the mattress when it is in its extended position (Fig. 1).

A suitable lock 11 is provided for fastening the door 3 in its closed position.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such 85 alterations or changes as shall fairly fall within the scope of the appended claims.

What I claim is:

1. In a trunk bed, the combination of a casing provided with drawers in its rear portion and with a compartment in its front portion, a mattress in the compartment against the drawers and holding the drawers in a closed position, and a door on the casing and closed against the mattress for holding the mattress in the compartment.

2. In a trunk bed, the combination of a casing provided with an open front and with a plurality of drawers in its back and

2
with a compartment formed between the front of the drawers and the open front of the casing, a sectional mattress folded together and in said compartment against the front of the drawers holding the drawers closed, and a door hinged to one of the edges of the front of the casing and closed

against said mattress and holding the same in the compartment, substantially as shown and described.

10

In testimony whereof I hereunto affix my signature.

FRED MOORE.
